DEVICE FOR FORMING AND PUNCHING METALS OR THE LIKE

Aloysius Joseph Bachewicz, Barrington, Ill., assignor to Barney Fagen, Westmont, Ill.

Application December 29, 1955, Serial No. 39,518

Term of patent 3½ years

(Cl. D54—13)

Figure 1 is a perspective view of a device for forming and punching metals or the like showing my new design; Figure 2 is a front elevational view of the same; Figure 3 is a right side elevational view thereof; and Figure 4 is a top plan view thereof.

I claim:
The ornamental design for a device for forming and punching metals or the like, as shown.
